MACHINE FOR YIELDABLY PRESENTING
WORK TO BUFFING OR POLISHING
WHEELS OR BELTSHenry G. Perkins, Kalamazoo, Mich., assignor to
Hammond Machinery Builders, Inc., Kala-
mazoo, Mich.

Application May 5, 1950, Serial No. 160,276

10 Claims. (Cl. 51—237)

1

This invention relates to improvements in machine for yieldably presenting work to a buffing or polishing wheel or belt.

The principal objects of this invention are:

First, to provide a machine having a rotatable and adjustable work holding spindle with means for yieldably shifting the spindle in its adjusted and rotating position.

Second, to provide a rotatable work support for polishing and buffing rounded objects which is operative to effectively present eccentric workpieces to a polishing or buffing element.

Third, to provide a standard for supporting a work holding head so that the head can be either yieldably or fixedly located in working position.

Fourth, to provide a novel form of disengagable spring loading mechanism for biasing a slide member on its support.

Fifth, to provide a novel form of releasable interlock between a slide member and its support.

Other objects and advantages relating to details of my invention will be apparent from a consideration of the following description and claims.

The drawings, of which there are two sheets, illustrate a preferred form of my yieldable mount for a work holding turret and spindles.

Fig. 1 is a fragmentary front elevational view of the support and work holding portions of my machine partially broken away in vertical cross section.

Fig. 2 is a horizontal cross sectional view taken along the plane of the line 2—2 in Fig. 1 with the work holding head removed and with a portion of the head supporting slide plate partially broken away in horizontal cross section.

Fig. 3 is a fragmentary side elevational view of the supporting standard and slide plate of the machine partially broken away in vertical cross section along the plane of the line 3—3 in Fig. 2.

Fig. 4 is a fragmentary horizontal cross sectional view taken along the plane of the line 4—4 in Fig. 3 and illustrating the lock mechanism for holding the slide plate in fixed position.

My machine is of the general type commonly used to present circular workpieces to a buffing or polishing wheel or belt and to rotate the workpiece so as to present the entire surface of rotation of the piece to the buffing or polishing element. To this end the machine is provided with a pedestal 1 having a transverse slideway 2 mounted thereon. A transverse slide member 3 is adjustably mounted on the slide 2 and in turn

5 forms longitudinal slideways 4. A longitudinal slide member 5 is adjustably supported on the slideways 4 and the longitudinal slide 5 serves to support an upright 6 on which a head 7 is supported.

10 The head structure 7 is commonly made angularly adjustable on the upright 6 in both horizontal and vertical planes and includes one or more work holding spindles 8 for receiving workpieces 9. In the example illustrated two spindles 8 are provided on a rotatable turret 10 and means including a driving motor, not illustrated, are provided for individually rotating the spindles and indexing the turret 10 to successively bring the spindles into opposed relationship with the polishing or buffing wheel 11. The structure thus far described is well-known and is described in general terms only to indicate the position and function of my yieldable head supporting structure which is positioned between the longitudinal slide 5 and the upright 6 and indicated generally by the reference character 12. Where desirable the head structure 7 may include mechanism for axially reciprocating the turret 10 and spindles 8 for moving long workpieces across the face of the polishing element 11.

20 My yieldable supporting structure 12 includes the ways 13 formed transversely on the top of the longitudinal slide member 5. The ways 13 operate through the balls 14 to slidably support the yielding slide plate 15. The plate 15, which is generally rectangular, is provided with downturned flanges 16 along its edges and with adjustable gibs 17 underneath its side edges. The gibs 17 coact with the balls 14 to support the slide plate 15 for sliding motion transversely of the machine. Removable end plates 18 on the left side of the slide plate permit the assembly of the balls 14 between the slideways 13 and gibs 17 and cushion headed bolts 19 mounted in the right side flange of the slide plate coact with the right side of the longitudinal slide member 5 to cushion the outward movement of the slide plate away from the polishing element 11. The slide plate 15 forms the immediate support for the upright 6 which is secured thereto by means of the screws 20.

25 The structure for yieldably biasing the slide plate 15 on the longitudinal slide 5 consists of an abutment bracket 21 secured to the left front corner of the longitudinal slide 5. The abutment bracket 21 carries a cam plate 22 having a laterally presented cam edge 23 and locking detent 24 formed thereon. Coacting with the cam edge 50 and detent 24 is a roller 25 rotatably mounted

on a piston-like support 26. The piston 26 is slidably mounted in a boss or bushing 27 formed on the underside of the hand operated lever 28. The lever 28 is pivotally supported at 29 on an ear 30 projecting from the right front corner of the slide plate 15. A coil spring 31 is compressed between an abutment on the fixed end of the lever and an adjustable nut 32 carried on a threaded pin 33 extending from the piston 26. A pin and slot connection 34 between the piston and bushing 27 keeps the roller 25 in the same plane as the cam plate 22 and limits the extension of the spring. It will be noted that the slide plate 15 is provided with an alternate ear 30A on its right rear corner so that the machine 15 can be easily adapted for right or left hand operation by simply mounting the abutment bracket 24 and lever 28 on the rear side of the slide plate and reversing the upright 6 on the slide plate.

When the lever 28 is swung inwardly to engage the roller 25 with the cam surface 23 and locking detent 24, the spring 31 is compressed urging the slide plate 15 and upright 6 toward the polishing element 11. Should the work-piece 9 mounted on the turret 10 be eccentric with respect to the spindle 8, the increased pressure of the eccentric portions of the work on the polishing wheel 11 will then cause the entire head and slide plate 15 to move rearwardly against the compression of the spring 31 and the spring will then function to return the concentric portions of the workpiece to the polishing element with sufficient pressure to obtain efficient polishing action all around the work-piece.

In order to permit the machine to be used without the previously described yielding action the longitudinal slide 5 is provided with an upstanding roller 35 near the center of its left hand edge. The roller is mounted on a screw 36 and projects upwardly into the path of a locking rotor 37 positioned in an upwardly offset, downwardly recessed portion on the left side of the slide plate 15. The rotor 37 is eccentrically mounted on a pin 38 and the pin is provided with an operating crank and handle 39 located on the top side of the slide plate. The rotor 37 is transversely slotted as at 40 so that operation of the lever 39 will position the rotor to either pass over the roller 35 or to lockingly engage the roller as illustrated in Fig. 4. With the rotor engaging the roller 35 the slide plate 15 cannot move away from the polishing element 11 and the engagement of the end plates 18 with the left edge of the longitudinal slide will prevent movement of the slide plate in the opposite direction. In the locked position of the slide plate, the lever 28 and roller 25 will normally be disengaged from the cam plate 22.

Having thus described my invention, what I claim as new and desire to secure by Letters Patent is:

1. In combination with a rotatable indexing turret having individually rotatable work holding spindles thereon, a support for said turret including superimposed longitudinal and transverse adjustable slide members, slideways extending transversely of said longitudinal slide member, a slide plate slidably mounted on said slideways, said turret being mounted on said slide plate, a cammed abutment on said longitudinal slide member, a lever pivotally secured to said slide plate and swingable across said abutment, a roller slidably mounted on said lever and arranged to coat with said abutment, a

spring adjustably compressed between said roller and the fixed end of said lever, a locking rotor having an operating lever and eccentrically rotatably mounted on said slide plate, a second roller projecting from said longitudinal slide member into the path of movement of said rotor, said rotor being slotted to selectively pass or engage said second roller, and travel limiting stops coacting between said longitudinal slide member and said slide plate in opposition to the locking action of said rotor and said second roller.

2. In combination with a rotatable work holding spindle, a support for said spindle including superimposed longitudinal and transverse adjustable slide members, slideways extending transversely of said longitudinal slide member, a slide plate slidably mounted on said slideways, said spindle being supported on said slide plate, a cammed abutment on said longitudinal slide member, a lever pivotally secured to said slide plate and swingable across said abutment, a roller slidably mounted on said lever and arranged to coat with said abutment, a spring adjustably compressed between said roller and a fixed position relative to said slide plate, a locking rotor having an operating lever and rotatably mounted on said slide plate, a second roller projecting from said longitudinal slide member into the path of movement of said rotor, said rotor being cut away to selectively pass or engage said second roller, and travel limiting stops coacting between said longitudinal slide member and said slide plate in opposition to the locking action of said rotor and said second roller.

3. In combination with a rotatable work holding spindle, a support for said spindle including superimposed longitudinally and transversely adjustable slide members, slideways extending transversely of the upper of said slide members, a slide plate slidably mounted on said slideways, said spindle being supported on said slide plate, a cammed abutment on said upper member, a lever pivotally secured to said slide plate and swingable into alignment with said abutment, a cam follower slidably mounted on said lever and arranged to coat with said abutment, a spring adjustably compressed between said cam follower and the fixed end of said lever, a locking rotor having an operating lever and rotatably mounted on said slide plate, a projection on said upper slide member in the path of movement of said rotor, said rotor being cut away to selectively pass or engage said projection, and travel limiting stops coacting between said upper slide member and said slide plate in opposition to the locking action of said rotor and said projection.

4. In combination with a rotatable work holding spindle, a support for said spindle including superimposed longitudinally and transversely adjustable slide members, slideways extending transversely of the upper of said slide members, a slide plate slidably mounted on said slideways, said spindle being supported on said slide plate, a cammed abutment on said upper member, a lever pivotally secured to said slide plate and swingable into alignment with said abutment, a cam follower slidably mounted on said lever and arranged to coat with said abutment, a spring compressed between said cam follower and a stop on said slide plate longitudinally fixed relative to said slide plate, a locking rotor having an operating lever and rotatably mounted on said slide plate, a projection on said upper slide

member in the path of movement of said rotor, said rotor being cut away to selectively pass or engage said projection, and travel limiting stops coaxing between said upper slide member and said slide plate in opposition to the locking action of said rotor and said projection.

5. In combination with a rotatable work holding spindle, a support for said spindle including superimposed longitudinally and transversely adjustable slide members, slideways extending transversely of the upper of said slide members, a slide plate slidably mounted on said slideways, said spindle being supported on said slide plate, a cammed abutment on said upper member, a lever pivotally secured to said slide plate and swingable into alignment with said abutment, a cam follower slidably mounted on said lever and arranged to coat with said abutment, and a spring compressed between said cam follower and a stop on said plate longitudinally fixed relative to said slide plate.

6. In combination with a rotatable work holding spindle, a support for said spindle including superimposed longitudinally and transversely adjustable slide members, slideways extending transversely of one of said slide members, a slide plate slidably mounted on said slideways, said spindle being supported on said slide plate, a cammed abutment on said one slide member, a lever pivotally secured to said slide plate and swingable into alignment with said abutment, a cam follower slidably mounted on said lever and arranged to coat with said abutment, a spring adjustably compressed between said cam follower and a stop on said plate longitudinally fixed relative to said slide plate, a locking member having an operating lever and rotatably mounted on said slide plate, a projection on said one slide member in the path of movement of said locking member, said locking member being swingable to selectively pass or engage said projection.

7. In combination with a rotatable work holding spindle, a support for said spindle including superimposed longitudinally and transversely adjustable slide members, slideways extending transversely of one of said slide members, a slide plate slidably mounted on said slideways, said spindle being supported on said slide plate, an abutment on said one slide member, a lever pivotally secured to said slide plate and swingable into alignment with said abutment, a follower slidably mounted on said lever and arranged to coat with said abutment, and a spring compressed between said follower and a stop on said plate longitudinally fixed relative to said slide plate.

8. In a machine for presenting workpieces to a finishing tool, the combination of a head having a rotatable work holding element thereon, a sup-

port member having slideways thereon, a slide member slidable on said slideways for motion toward and away from said tool, said head being carried by said slide member, means for biasing said slide member and head toward said tool including a lever pivotally mounted on one of said members, a cammed abutment on the other of said members and spaced from the pivot of said lever, a movable spring abutment carried by said lever and swingable therewith into and out of engagement with said cammed abutment on said other of said members, a compression spring adjustably compressed between said movable abutment and said one of said members, and a stop on said lever limiting the extension of said spring and said movable abutment.

9. In a machine for presenting workpieces to a finishing tool, the combination of a head having a rotatable work holding element thereon, a support member having slideways thereon, a slide member slidable on said slideways for motion toward and away from said tool, said head being carried by said slide member, means for biasing said slide member and head toward said tool including an operating handle mounted on one of said members, a cammed abutment on the other of said members and spaced from said handle, a movable spring abutment carried by said handle and movable therewith into and out of engagement with said cammed abutment on said other of said members, a compression spring compressed between said movable abutment and said one of said members, and a stop on said handle limiting the extension of said spring and said movable abutment.

10. In a machine for presenting workpieces to a finishing tool, the combination of a head having a rotatable work holding element thereon, a support member having slideways thereon, a slide member slidable on said slideways for motion toward and away from said tool, said head being carried by said slide member, means biasing said slide member and head toward said tool, and a manually operable disengaging member for selectively disengaging said biasing means from operative engagement with said slide member.
